UNITED STATES PATENT OFFICE

GILBERT L. MATTHIAS, OF CUYAHOGA FALLS, OHIO, ASSIGNOR TO THE B. F. GOODRICH COMPANY, OF NEW YORK, N. Y., A CORPORATION OF NEW YORK

CHANNEL-STRIP MATERIAL AND METHOD OF MAKING THE SAME

Application filed January 13, 1927. Serial No. 161,009.

This invention relates to channel strip material such as is used for cushioning the window glasses of automobiles.

Its chief objects are to provide for economy 5 of manufacture; to provide a channel strip having highly resilient and deformable cushioning members adapted snugly to embrace the glass and prevent rattling; to provide a channel strip adapted resiliently to 10 engage the glass and yet to remain in an extended condition without anchoring of its ends and not buckle under the frictional force of the glass; and to provide these advantages in a channel strip presenting to the 15 glass a fibrous, anti-friction surface.

Of the accompanying drawings:

Fig. 1 is a perspective view of a piece of channel strip embodying and made in accordance with the preferred form of my in- 20 vention.

Fig. 2 is a perspective view of a piece of channel strip of modified construction.

Fig. 3 is a perspective view of another modification.

25 Referring to the drawings, the channel strip shown in Fig. 1 comprises a flat base strip 10 upon which is secured a pair of cushioning leg-members of which each comprises a tubular core 11 of resilient rubber 30 and a fibrous covering 12 thereon, the coverings here being shown as consisting of a single strip of fabric having its respective marginal portions folded laterally about the cores 11 and sewed to the base member 10 at 35 the inner corners of the legs, as indicated at 13, 13, to secure the legs to the base. In the embodiment of Fig. 1 the hollow cores 11 are each of approximately rectangular cross-section, to provide a channel having walls 40 approximately parallel in cross-section, but preferably are of such cross-section as to cause the legs to converge slightly toward each other so as to embrace snugly a window glass of less thickness than the width of the 45 bottom of the channel and to contact the glass at their outer edges and thus to provide a snug fit and an effective cushioning of the glass.

The fibrous covering 12 is preferably of 50 anti-friction material such as felt and the

base member 10 is preferably of a stiff, fibrous composition such as rubber-impregnated fiber, rag stock or fiber board.

The anchoring of the leg members to the base member 10 at their inner corners by the stitching 13 holds them against the spreading force of the glass received between the two legs, and the hollow form of the core members 11 permits the legs resiliently to yield to accommodate the glass while snugly 60 embracing the latter with a moderate pressure. The hollow form of the cores also provides legs of desired cross-section with a comparatively small amount of rubber.

In the modification shown in Fig. 2 substantially the same effects are secured by substituting sponge-rubber core members 14, 14 for the hollow core members 11 of Fig. 1.

In Fig. 3 the rubber core members, 15, 15, are tubular and of round cross-section, providing a channel having rounded inner walls so that the legs will snugly embrace a window glass of less thickness than the width of the bottom of the channel and thus provide a snug fit for window glasses of varying thickness, the round form of the cores providing a wide range of deformability without such opening out of the channel legs as to cause them to stand away from the glass throughout their height.

In all of these embodiments the core members, 11, 14 or 15, are preferably formed and vulcanized before their incorporation in the channel strip and the base member 10, when it comprises rubber, is preferably vulcanized before its incorporation in the strip. The several elements of the complete strip, each of simple character and inexpensive to manufacture, are readily assembled and secured in position by the stitching 13, and thus a laterally resilient, non-stretching and non-buckling channel strip, having an anti-friction fibrous surface, is produced. The employment of the tubular rubber or the sponge rubber core members provides a high degree of cushioning and also permits temporary deformation of the core members to facilitate the stitching operation without resulting looseness of the coverings or weakening of the grip of the channel legs upon the glass,

the hollowed, vulcanized, rubber strips, whether of the tubular form or of the sponge-rubber form, having a wide range of resilient deformability.

5 Further modifications are possible within the scope of my invention as defined in the appended claim.

I claim:

10 A channel strip comprising a base, legs comprising sponge-rubber extending from said base, and fibrous cover material on said legs.

15 In witness whereof I have hereunto set my hand this 8th day of January, 1927.

GILBERT L. MATTHIAS.
